PROCESS AND APPARATUS FOR DELINTING COTTON SEED HULLS

Filed June 2, 1924

Patented Aug. 16, 1927.

1,639,568

UNITED STATES PATENT OFFICE.

THOMAS J. KIDD, OF BIRMINGHAM, ALABAMA.

PROCESS AND APPARATUS FOR DELINTING COTTONSEED HULLS.

Application filed June 2, 1924. Serial No. 717,224.

This invention relates to certain new and useful improvements in a method of, and mechanism for, the manufacture or production of fiber from cotton seed hulls.

5 The main object of my invention is to effect mechanically a separation of the hull skins from the fiber in such manner that the hull skins can be discharged at a different point from the fiber, thus producing a fiber 10 of higher grade and greater value than where it is produced in combination with the skins and enabling me at the same time by virtue of my manner of separation to obtain from the machine a very large output.

15 My invention contemplates the utilization of a plurality of rapidly moving cutters to effect a separation of the fiber from the skins, as contrasted with grinding or beating operations by which the hulls are disintegrated.

20 Further, my invention contemplates the utilization and control of air currents working against centrifugal force where the skins are ejected and working with centrifugal force where the fiber is discharged, these 25 currents being controllable and so related to the size of the skin particles and the action of centrifugal force thereon that only the skin particles will reach their point of discharge and that practically all of the skin 30 particles will be there discharged, leaving present in the fiber as foreign matter only a relatively small percentage of skin dust which can be readily removed by cyclones or equivalent mechanism.

35 My invention further contemplates the provision of a hull treating machine comprising an inlet for the hulls, a treating chamber in which the knives or thin edged blades, assembled on the rotor, work and 40 which has on one side a screen or skin outlet with relatively large openings through which the hull bran or skins are discharged preferably against inflowing air and on the other side a screen or fiber outlet with relatively 45 small openings through which the fiber is discharged with the outflowing air to a suitable duct.

50 My invention also contemplates improvements in the design of the rotor in that it is provided throughout its length within the machine with very closely associated disks connected axially by cutter blade shafts upon which are mounted for the length of the machine closely associated thin cutter blades 55 which present sharp angles of impact to act on the hulls and strip the fiber from

the heavier skin parts in the induced hull whirl.

My invention also contemplates improvements in the construction of these cutter 60 blades whereby they are reversible to obtain maximum service therefrom.

My invention also contemplates the novel details of construction and arrangements of parts, which in their preferred embodiment 65 only are illustrated in the accompanying drawings, and which are described more fully in the specification following and in the claims appended thereto.

According to the drawings:

70 Fig. 1 is a vertical cross-sectional view through a typical embodiment of my invention.

Fig. 2 is a detail view enlarged of a section of the rotor showing the preferred manner 75 of assembling the knife blades thereon.

Fig. 3 is a plan view on a reduced scale of Fig. 1.

Similar reference numerals refer to similar parts throughout the drawings.

80 In the embodiment of my invention illustrated, cotton seed hulls, preferably by a regulated and graduated feed, are delivered by means of an inclined chute 1 to the top feed opening 2 of the machine. This opening is restricted by an inclined perforated screen 3 which at its lower end merges into a perforated concave 4 terminating at the upper end of a filler block 5 suitably attached to the lower front wall 6 of the machine. 85 An inclined chute 7 leads from the base of the concave 4 through a skin outlet 8 disposed below the upper removable front section 9 of the machine. It will be observed that the feed opening 2 as thus restricted is set so as to deliver the hulls to one side of the rotor in the machine. The metal base of the machine comprises a front wall 10, a hopper bottom 11 and a back wall 12, and the front wall has an inwardly overhung flange 13 which is protected by an angle iron 14 and from which depends the forward edge of a perforated bottom half circular concave 15, the rear side of which is supported from a flange 16 overhung from the back wall of the base. The concave 15 is struck on a center from the rotor shaft 17 and is closely spaced from the outer ends of the cutting blades 18 which are mounted peripherally about the rotor in the manner 95 which will be later described. Above the flange 16 are mounted metal baffle plates 19

100

105

110

which are corrugated and are spaced much further from the cutter blades than the concave 15. These plates extend the full length of the machine and terminate at the back wall 20 of the feed opening 2. A solid metal cover 21 is mounted over the baffle plates. The hopper 11 is connected by a pipe 22 with the intake of a suction fan 23 having a discharge pipe 24 leading to a cyclone or equivalent machinery, which, forming no part of my present invention, is not disclosed.

The perforations in the fiber screen concave 15 are of materially smaller diameter than those in the skin screen 4, having approximately from 1/6th to 1/3rd. of the diameters of the holes in the screen 4. While the sizes of these perforations may be varied according to operating conditions and the results desired, I have obtained satisfactory results by the use of perforations having a diameter of from 3/16ths to a quarter of an inch in the skin screen 4 and which are very closely associated, and with openings of from 1/16th to 1/32nd of an inch also closely associated in the fiber screen 15. The suction fan is calculated to induce a draft of air through the feed opening 2 and through the screens 3 and 4 and through the skin outlet 8. The velocity of the air currents entering the working chamber through the concave 4 is determined empirically, the currents being of correct velocity when, having regard for the R. P. M. of the rotor and the centrifugal action of the rotor on the skins, they will permit only the skins to escape through the concave 4 while forcing the fiber to follow around with or work through between the cutter blades to the concave 15. Obviously as this condition of maximum efficiency is approached greatly increased benefits will be obtained from the machine and my invention contemplates its operation at or approaching the conditions above described for maximum efficiency.

The rotor is shown, in its preferred embodiment, made up as follows. I key on the shaft 17 within the machine a series of spaced disks 25, which disks are connected about their peripheries with a series of axially disposed cutter blade shafts 23 which preferably extend the full length of the machine. On these shafts and between the disks I mount a plurality of very thin cutter blades 18 which are preferably loosely mounted on each shaft 26 and arranged in groups between adjacent disks on each shaft. The cutter blades are preferably formed of very thin steel stock such as that from which gin saws are made, being preferably about 35/1000ths of an inch in thickness and in length being adapted to travel when in radial position with their outer ends in close proximity to the fiber concave 15 but not in contact therewith. These blades are sheared

to provide sharp corners or angles of impact and they will work with decreasing efficiency as the sharp forward corner angle and working edges wear away. It is desirable that the disks shall be as thin as is compatible with the duty required of them, those in use being formed from plate not exceeding a quarter of an inch in thickness and these are spaced so that in the aggregate they have the requisite strength to support the shaft 26. On each shaft 26, between adjacent disks, I mount the cutter blades in close association, which however will leave a slight spacing between them.

It is my present theory of the action of this machine that these closely associated cutter blades must strike the entering cotton seed hulls and convert them by their combined impact into relatively large particles of skins and into fiber, and that this action will occur as the cotton seed hulls enter the working chamber and will be accomplished during the one or more impacts that may occur between a hull and successive series of cutter blades as the hull moves around towards the concave 4 and around the treatment chamber. In the machine as I have heretofore manufactured it the distance from center of the rotor to the tip of the cutter blade has been approximately 12 inches and the rotor has been driven at around 2000 R. P. M. In operation, a thin belt or whirl of comminuted hulls having more or less fiber adhering to them exists about the rotor disks which I am of opinion is one constantly changing and largely replaced from the material which collects in the chamber under the baffle plates where the larger particles will collect and be treated in the working portion of the chamber by the action of the rotor until the hull skins are stripped of the fiber adhering thereto. I consider it advantageous to effect a separation of the fiber from the hull bran as the fiber is freed from the skin particles and to this end my invention utilizes a forcible air current flowing through the whirling mass of material under treatment to entrain and carry out with it the fibers as they become detached, the hull skins or bran particles as they become stripped of fiber being ejected by centrifugal force. It is essential that the hulls shall be fed in a graduated manner and that the machine shall not be choked as under such conditions it will not perform the contemplated functions. By having such a regulated feed there is preserved ample space between the cutter blades and the skin concave 4 to give the separated fiber and skins opportunity to have an appreciable flight when struck by the rotor blades, thereby giving the inflowing air currents time and opportunity to retard or deflect the lighter particles of fiber while permitting the heavier skin particles to strike, or pass di-

rectly through the openings in the concave 4 or, as they pass downwardly over the concave to escape through a staggered opening therein. From this it necessarily follows 5 that the openings in all of the screens or outlets should be staggered. The knife blades are provided with squared ends and with aligning holes 27 at their ends which permit the blades when they become worn to be 10 both turned and reversed.

In the operation of my invention, assuming a graduated feed of hulls flowing down the chute 1 and the rotor driven at proper speed with the fan inducing by its suction 15 air currents which enter the working chamber through the feed opening 2 and screen 4, as the entering and rotating hulls are struck or engaged by the fast spinning cutter blades they are both cut and centrifugally 20 ejected towards the screen concave 4 and the particles of skin or woody parts of the hulls, from which the cutter blades have stripped the fiber, will have sufficient momentum and weight to overcome any opposing air currents and escape through the screen 4 and 25 pass off through the discharge opening 8 and the discharge chute 7 to be collected for use as defibrated hulls or hull bran for mixed cattle feeds. The particles of lint or fiber which adhere to the skin particles and follow 30 the travel of the cutter blades towards and pass over the concave 15 will, as stripped from the skin by the cutting action of the faster traveling blades, be drawn through 35 the openings in this concave by the action of the air currents and delivered by the suction fan and connection shown to dust separating means and thence discharged as commercial fiber. The blades are arranged so 40 as to permit the free transverse or diametric flow of the air current across the chamber so that the fiber as released at any point in its whirl about the axis of the chamber will become entrained in said current and pass 45 more or less directly through the fiber outlet. This fiber being substantially free of hull skins and dust is of the highest market 50 grade and available for use in the manufacture of artificial silk, high grade paper stock, cellulose, and the like. The absence of any 55 appreciable quantity of the skins in the fiber greatly reduce the cost of purifying and bleaching it, thus further increasing its commercial value.

55 In my earlier experiments where the machine was operated on the beater principle, with a pulverizing or grinding effect on the hulls from beaters of the hammer type, and with a common bottom outlet for the total 60 pulverized or reduced product, a low grade fiber was produced from which it was practically impossible to effectively separate the woody matter forming the skins and the maximum capacity of the machine was 65 less than one-third of the capacity of

the machine as converted to the present type of cutting machine, and the earlier type of machine ground the woody matter almost to dust and this so thoroughly impregnated the fiber that it was practically 70 impossible to thoroughly clean the fiber of the woody matter. This resulted in a grade of fiber which is expensive to purify and bleach and due to the fact that it would have to remain in the machine until the 75 whole product was dissolved there was produced a length of fiber so short as to be of relatively small value. I consider it a most important feature of my method of treatment that the skins are disintegrated as little 80 as possible in order to separate them from the fiber. The larger the skin particles the easier they are to separate from the fiber and the better the quality of the fiber product and for this reason I have designed my machine to operate on the principle of cutting or thrashing the hulls instead of grinding or 85 pulverizing them. Moreover, the cutter edge which does the cutting or stripping of the fiber from the skins may be a transverse 90 edge or one or more longitudinal edges or corners of the blade, or all of such edges, and when such cutting edges are relied on, thicker blades may be employed to deliver 95 to the hull particles the blows which will separate the fiber from the skins, and by being drawn at greater velocity through the belt or whirl of partially defibrated hulls, to strip the fiber from the skins by a cutting 100 action.

By centrifugal separation of the skins from the fiber I mean to include any utilization of the action of the blades as they strip or cut the fiber from the skins, on the skin particles to throw the latter through the 105 screen 4, whether such flight of the skin particles be the result of impact from the blades or the result of contact of the hulls with the fast spinning blades which would act to both strip the fiber from the skin and 110 eject the heavier skin particles.

Where the term screen is used I mean thereby to include any part of the apparatus which is provided with openings suitable on the one hand for the escape of the hull skins and on the other for the escape of the air current with the freed fiber and such small particles of hull skins and dust as become entrained therein. By a diametric flow of the 115 air current through the hull whirl I mean any transverse flow which will follow a general radial direction through the chamber.

Though I have described with great particularity the details of the embodiment of the invention herein shown, it is not to be construed that I am limited thereto, as changes in arrangement and substitution of equivalents may be made by those skilled in the art without departing from the invention as defined in the appended claims.

Having thus described my invention, what I claim as new and desire to secure by Letters Patent, is:—

1. In a defibrating machine for cotton seed hulls and the like, a defibrating chamber having a hull inlet, a rotor having a multiplicity of fast spinning cutter blades adapted to separate fiber from the hull skins and drive the hulls in a peripheral whirl about said chamber, means to induce a strong air current to traverse the chamber and the whirling mass of hulls, and means to permit the escape of the defibrated hull skins, there being a multiplicity of small outlets for the air with the entrained fiber over which the blades are adapted to drive the larger hulls and skin particles.

2. A defibrating mechanism according to claim 1, in which the rotor on which the cutter blades are mounted is a rotating spider adapted to permit the free transverse flow of the air current across the defibrated chamber.

3. A defibrating mechanism according to claim 1, in which the cutter blades are flat with squared corners and pivotally mounted upon the rotor to present their edges to the work.

4. A defibrating mechanism according to claim 1, in which the cutter blades are formed of short thin flat metal strips each blade being reversible about its longitudinal and transverse axis to provide four duplicate working portions, and means to mount said blades free for reversal on the rotor.

5. A defibrating machine for cotton seed hulls and the like, comprising a substantially annular chamber provided with a hull inlet and spaced peripheral apertures for the transverse flow of a strong air current therethrough, the apertures on one side being larger for the escape of defibrated hull skins counter to inflowing air and responsive to centrifugal force, and on the other side smaller for the escape of the freed fiber, means to induce said air current, and a rotor carrying closely associated cutter blades disposed with their outer ends traveling in close proximity to the chamber wall opposite the fiber outlet apertures, the chamber being enlarged on its hull inlet side, and the cutter blades having working edges which engage the hulls in the whirl to both induce their rotation and to strip the fiber therefrom.

6. A mechanism for defibrating cotton seed hulls and the like, comprising a working chamber containing fast spinning cutters adapted to separate the fiber from the hull skins, in combination with a screen, in the path of the separated hull skins as centrifugally ejected, through which the skins escape from the working chamber, a separate screen for the escape of the fiber, and

means to induce a draft to flow outwardly through said latter screen.

7. A mechanism for defibrating cotton seed hulls, comprising a working chamber having a feed opening and containing fast spinning cutters, a foraminous screen for the escape of skins in one portion of said working chamber, a foraminous screen for the escape of fiber in another portion of said working chamber, means to induce currents of air inwardly through the feed opening and outwardly through the fiber screen, and means to feed the hulls to the cutters.

8. A mechanism for the separation of fiber from cotton seed hulls according to claim 6, in which the fast spinning cutters are in the form of thin closely associated edged blades mounted on a rotor.

9. A machine for the separation of fiber from cotton seed hulls, comprising a separating chamber having a hull inlet, a rotor mounted in the chamber and comprising axial series of closely associated blades disposed about its periphery, two screens disposed in the plane of rotation of the blades, one having apertures large enough for the escape of skin particles, and another having relatively small openings for the passage of fiber, and means to induce air currents to flow through the working chamber and screens, substantially as described.

10. A machine for the separation of fiber from cotton seed hulls according to claim 7, in which the screen for the skins is substantially spaced from the rotor at its upper edge and gradually approaches the path of the moving blades towards its lower edge.

11. A machine for the separation of fiber from cotton seed hulls according to claim 7, in which the fiber screen is concave and set close to and substantially concentric with the path of the rotating blades while the skin screen is concave and disposed eccentric to the path of the blades and substantially spaced therefrom.

12. A machine for the separation of fiber from cotton seed hulls, comprising a working chamber having a top hull feed inlet, a rotor working in said chamber and having axial series of closely associated very thin blades pivotally mounted about its periphery, a screen mounted on the side of the chamber beyond the hull inlet in the direction in which the knives rotate and comprising a concave eccentric to the path of the knives and approaching the latter towards the lower edge and having relatively large perforations for the free inflow of air and the free escape of relatively larger skin particles, a screen concave forming the lower portion of said working chamber and disposed substantially concentric with the path of the blades and provided with relatively small openings suitable for the escape of

fiber, and means to induce forcible air currents which enter the working chamber through the skin screen and escape therefrom through the fiber screen.

5 13. The herein described process for the separation of fiber from cotton seed hulls and the like, which consists in severing the fiber from the skins by the action of edged blades applied to the hulls while traveling 10 through an annular defibrating chamber and in the presence of a strong air current flowing counter to the escape of cleaned hull skins.

14. The herein described process for the separation of fiber from cotton seed hulls and the like, which consists in stripping the fiber from the skins by the action of cutting edges applied to the hulls while traveling 15 in a whirl across an air current, causing the hull skins to escape against the air flow to a discharge separate from that of the fiber, and entraining the fiber in and causing it to escape with said current as it is freed from the hull skins.

20 15. The herein described process for the separation of fiber from cotton seed hulls and the like, which consists in causing the hulls while under treatment to travel in a thin whirling mass across a positively induced air current, removing the hull skins from the whirl by centrifugal force exerted counter to the air current, freeing the fiber by the action of edged blades driven through the mass of hulls entraining the 25 fiber in the air current and removing it through a screen, and feeding hulls to maintain the desired limited quantity in the whirl.

30 16. The herein described process for the defibration of cotton seed hulls and the like, which consists in causing the hulls while under treatment to move in a thin whirling mass exposed to an air current, stripping the fiber from the skins by the action of thin 35 blades driven edgewise through the whirling mass centrifugally ejecting from the whirl and removing from the chamber the cleaned hull skins, entraining the freed fiber in said current causing the air current to escape with the fiber, restraining the hulls from following the outgoing fiber, and replenishing the mass of hulls in the whirl.

40 17. The herein described process for the production of fiber from cotton seed hulls and the like, which consists in producing a whirl of the mass of hulls under treatment and causing same to travel across the path of a strong air current, stripping fiber from the hull skins by blades having movement 45 relative to the hulls, causing the larger skin particles to escape against the air current as they become cleaned of fiber to the desired extent, entraining the fiber, as stripped, in the air current to remove it from the whirling mass, and screening the outgoing air

to prevent the escape of hulls and skins therewith.

18. The herein described process for the production of fiber from cotton seed hulls and the like, which consists in producing a 70 whirl of the mass of hulls under treatment across the path of an induced air current free to flow substantially diametrically through the whirl, stripping fiber from the hull skins by thin sharp cornered blades having movement relative to the hulls, causing the larger skin particles to escape by centrifugal force exerted against the air current as they become cleaned of fiber to the desired extent, and entraining the fiber, as 75 stripped, in the air current and removing it from the whirling mass.

19. The herein described process for the production of fiber from cotton seed hulls and the like, which consists in producing a 80 whirl of the mass of hulls under treatment across the path of an induced air current flowing across the whirl, stripping fiber from the hull skins by cutters having movement 85 relative to the hulls, causing the larger skin particles to escape against the air current as they become cleaned of fiber to the desired extent, entraining the fiber, as stripped, in the air current and removing it from the whirling mass, and causing the whirling hulls under treatment to expand and contract 90 radially in each cycle.

20. The herein described process for the production of fiber from cotton seed hulls and the like, which consists in producing a 100 whirl of the mass of hulls under treatment across the path of a strong transverse air current, stripping fiber from the hull skins by cutters having movement relative to the hulls, causing the larger skin particles to escape against the air current as they become cleaned of fiber to the desired extent, entraining the fiber, as stripped, in the air 105 current and removing it from the whirling mass, and causing the whirling hulls under treatment to expand and contract radially 110 in each cycle, the expansion being provided in the path of the entering air and the contraction in the path of the outgoing fiber laden air.

115 21. The herein described process for the production of fiber from cotton seed hulls and the like, which consists in producing a whirl of the mass of hulls under treatment across the path of an induced air current, stripping fiber from the hull skins by edge 120 blades having movement to the hulls, causing the larger skin particles to escape against the air current as they become cleaned of fiber to the desired extent, entraining the fiber, as stripped, in the air current and removing it directly from the whirling mass, causing the whirling hulls under treatment to expand and contract radially in each cycle, the expansion being provided in a po- 125

- sition to facilitate the centrifugal ejection of stripped skins from the mass against the inflowing air, and the contraction being provided to increase the relative movement between hulls and cutters in the path of the outgoing air.
22. The herein described process for the production of fiber from cotton seed hulls and the like, which consists in causing the mass of hulls while under treatment to travel rapidly in a whirl across a strong induced air current, driving blades edgewise through the whirling mass to strip the fiber from the hull skins, entraining the fiber in said current, screening the outgoing air to prevent the escape therewith of hulls and large skin particles, and ejecting the stripped skins from the whirl by centrifugal force exerted counter to the air current.
23. The herein described process for the production of fiber from cotton seed hulls and the like, which consists in causing the mass of hulls while under treatment to travel rapidly in a whirl across a strong induced air current, driving cutters through the whirling mass to strip the fiber from the hull skins, entraining the fiber in said current and removing it from the whirl as it is freed from the skins, ejecting the stripped skins from the whirl by centrifugal force exerted counter to the air current, and causing the mass in the whirl to loosen up when approaching the skin discharge.
24. The herein described process for the production of fiber from cotton seed hulls and the like, which consists in causing the hulls while under treatment to travel rapidly in a thin whirling mass across a strong air current, driving thin square cornered blades through the whirling mass to strip the fiber from the hull skins, entraining the fiber in said current and screening the outgoing air to cause it to remove from the whirl only the fiber as freed from the skins and small skin particles, ejecting the stripped skins from the whirl by centrifugal force exerted counter to the air current, causing the mass in the whirl to loosen up when approaching the skin discharge, and gradually feeding hulls to the whirl where the mass is loosened up.
25. A method of defibrating cotton seed hulls and other fibrous material, which consists in feeding such material into a treatment chamber, removing the fiber from the heavier hull particles by the stripping action of rapidly rotating cutter blades moving through a whirling mass of said material, removing the cleaned hull particles by centrifugal action, and removing the fiber with outflowing air.
26. A method of defibrating cotton seed hulls and other fibrous material, which consists in feeding such material into a treatment chamber, removing the fiber from the heavier hull particles by the action of rapidly rotating cutter blades moving through a whirling mass of said material, removing the hull particles centrifugally, and removing the fiber with outflowing air.
27. A method of defibrating cotton seed hulls and other fibrous material, which consists in feeding such material into a treatment chamber, removing the fiber from the heavier hull particles by the stripping action of edged blades, removing the hull particles against inflowing air, and removing the fiber with outflowing air through a screened outlet.
28. A method of defibrating cotton seed hulls and other fibrous material, which consists in feeding such material into a treatment chamber, removing the fiber from the heavier hull particles by the stripping action of edged blades, removing the hull particles centrifugally against inflowing air, and removing the fiber with outflowing air through a screened outlet.
29. A method of defibrating cotton seed hulls and other fibrous material, which consists in feeding such material into a treatment chamber, causing it to whirl about said chamber, removing the fiber from the heavier hull particles by the stripping action of edged blades, removing the hull particles against inflowing air, and removing the fiber with outflowing air, causing the mass in the whirl to have radial expansion and contraction in each cycle.
30. A machine of the character described, comprising in its organization, a treatment chamber having separate outlets, one for fine light material and the other for coarser heavier material, a feed inlet for the material to be treated, a multiplicity of edged cutters arranged in said chamber, means to drive the material into a whirl about said chamber and subject it to the action of said cutters to effect its separation into its coarse and fine component parts, and means to cause a draft to flow outwardly from the chamber through the fine material outlet bearing with it the said fine component parts.
31. A machine of the character described in claim 30, in which the cutters are thin straight-edged blades mounted on a rotor in the treatment chamber.
32. A machine of the character described in claim 30, in which the cutters are formed of thin flat metal with corner edges that present sharp angles of impact to the material under treatment.
33. A machine of the character described in claim 30, in which the outlets are protected by screens disposed in the path of the whirling material.
34. A machine of the character described in claim 30, in which the cutters present, in each of a plurality of closely associated par-

allel planes disposed at right angles to the axis of the whirl, a plurality of corner edges to act on the material in the whirl.

35. A defibrating machine for cotton seed hulls, according to claim 30, in which the chamber comprises a casing surrounding the cutters, said casing having a screen, concentric with said whirl, spaced away from that portion of the casing containing the fine

material outlet, whereby a chamber is formed 10 between said screen and last mentioned portion of the casing, and the means for causing the outflowing draft acts to exhaust air from said casing through said fine material outlet. 15

In testimony whereof I affix my signature.

THOMAS J. KIDD.
